Hamilton & Graavit, Jr.

UNITED STATES PATENT OFFICE.

ALFRED T. HIBBARD, OF LINCOLN, NEBRASKA, ASSIGNOR OF ONE-HALF
TO CARLETON C. JEROME, OF SAME PLACE.

GUNSTOCK.

SPECIFICATION forming part of Letters Patent No. 371,886, dated October 18, 1887.

Application filed February 19, 1887. Serial No. 228,227. (No model.)

To all whom it may concern:

Be it known that I, ALFRED T. HIBBARD, a citizen of the United States, residing at Lincoln, in the county of Lancaster and State of Nebraska, have invented certain new and useful Improvements in Gunstocks; and I do hereby declare the following to be a full, clear, and exact description of the invention, such as will enable others skilled in the art to which it appertains to make and use the same.

My invention relates to improvements in gunstocks; and it consists in constructing the stock of a gun in two parts and uniting them in an adjustable joint, as hereinafter described; and the object of my invention is to provide means whereby the stock may be lowered or dropped relatively to the barrel or barrels of the gun, as may be desired.

The accompanying drawings illustrate my invention.

Figure 1 is a side view of a gunstock embodying my invention. Fig. 2 is a side view in perspective of my improvements detached from the stock. Fig. 3 is a detailed view in perspective of the stock-socket of my invention, and Fig. 4 is a detailed view in perspective of the shoulder or cap of my invention.

Similar letters refer to similar parts throughout the several views.

30 The letter A, Fig. 1, represents a gunstock, which is divided into two parts, B and C.

The letter D, Fig. 2, (shown in detail in Fig. 3,) represents a socket provided with a shoulder, D', the arm E extending backward from the upper portion of the socket D, and the arm F extending backward from the lower portion of the socket D.

The part B of the stock is formed with grooves upon its fore end, upper and lower sides, for the reception of the socket-shoulder D' and arms E and F of the socket D. The socket D is firmly fastened to the part B of the stock by means of the screws or bolts e and f, or other ordinary device.

45 The letter d', Fig. 3, represents a screw-hole in the socket D for the reception of the screw G, and the letter d represents screw-holes for the reception of the set-screw g.

The letter H, Fig. 2, (shown in detail, Fig. 50 4,) represents a shoulder or cap provided with a shoulder, H', the arm I, extending forward from the lower portion of the cap H, and the

arm J, extending backward from the upper portion of the cap H.

The part C of the stock is formed with 55 grooves upon its rear end, lower and upper sides, for the reception of the shoulder H' and arms I and J of the cap H. The cap H is firmly fastened to the part C of the stock by means of the screws or bolts i and j, or other 60 ordinary device.

The letter h', Fig. 4, represents a screw-hole in the cap H for the reception of the screw G, and the letter h represents screw-holes for the reception of the set-screw g. The cap H is suitably curved so as to fit snugly into the socket D, and thus form an adjustable joint. The screw-hole d' in the socket D is made larger than the corresponding screw-hole, h', in the shoulder H, for the purpose of allowing an upward and downward movement in the joint, as may be desired. The screw-holes d in the socket D and h in the cap H are so relatively arranged that there will be in the socket D but one screw-hole, which in any given position 75 will have any corresponding screw-hole in the cap H for the reception of set-screw g.

The method of using my improvement is as follows: The cap H is first firmly fastened to the part C of the stock by means of the bolts 80 i and j, passing through the arms I and J and into the wood-work of the stock. Then the socket D is placed against the cap H in its desired relative position, and the set-screw g is then adjusted into the two screw-holes d and 85 h, which may correspond. The screw G is then adjusted into the screw-holes d' and h', and the socket D is then firmly fastened to the part B of the stock by means of the bolts or screws e and f, passing through the arms E and F and 90 into the wood-work of the stock. When the parts are thus placed together, the screws by which the two parts of the joint are united and held in their adjusted position are entirely confined and protected by the portion B of the 95 stock, thus preventing accidental displacement or removal, protecting them from dampness and rust, and also giving to the gunstock a very neat and finished appearance, much more so than if these adjusting elements were exposed.

Having thus described my invention, I claim as new and desire to secure by Letters Patent—

1. The combination of the part C of the gun-

stock, cap H, secured thereto and provided with screw-hole h' and a series of holes, h, socket D, adapted to cap H and having enlarged screw-holes d', and also having a series 5 of holes, d, screw G, projected through the hole d' into hole h', set-screw g, adapted to pass through the registering apertures h and d, and the part B of the stock, detachably secured to the socket D to cover and protect the projecting ends of the screws G and g after the parts 10 have been adjusted and secured together, substantially as described.

2. The combination, in a gunstock, of the part B of the stock, having the socket D thereto 15 attached by means of the arms E and F and

bolts e and f, and the part C of the stock, having the cap H thereto attached by means of the arms I and J and bolts i and j, and united in an adjustable joint by means of the screw G, passing through the openings or screw-holes 20 d' and h', and the set-screw g, passing through the opening or screw-hole d and the corresponding opening, h, substantially as described.

In testimony whereof I affix my signature in presence of two witnesses.

ALFRED T. HIBBARD.
